tion of Minnesota

Application April 29, 1950, Serial No. 9,592

Term of patent 14 years

(Cl. D44—29)

To all whom it may concern:

Be it known that I, Le Emmette V. de Fee, a citizen of the United States, residing in St. Paul, county of Ramsey, and State of Minnesota, have invented a new, original, and ornamental Design for a Combination Bottle Opener, Screw Driver, and Lid Opener, for which the following is a specification, reference being had to the accompanying drawing, forming part thereof.

Figure 1 is a plan view of a combination bottle opener, screw driver, and lid opener, showing my new design as it appears on either side.

Figure 2 is a side edge view thereof.

Figure 3 is a side edge view thereof opposite to that shown in Figure 2.

I claim:

The ornamental design for a combination bot-
tle opener, screw driver, and lid opener, as shown
and described.

LE EMMETTE V. DE FEE.
